(57) **CLAIM**

The ornamental design for a full boot for tandem type rod end, as shown and described.

DESCRIPTION

FIG. 1 is a front view of a full boot for tandem type rod end, showing our new design;

FIG. 2 is a rear view thereof;

FIG. 3 is a top plan view thereof;

FIG. 4 is a bottom plan view thereof;

FIG. 5 is a view thereof from the right of FIG. 1;

FIG. 6 is a view thereof from the left of FIG. 1;

FIG. 7 is a cross-sectional view taken on the line 7—7 of FIG. 3; and,

FIG. 8 is a perspective view thereof, with an additional rod end shown in a connected position.

The broken lines shown in FIG. 8 illustrate a second rod end in a connected position, and environmental structure, and form no part of the claimed design.
